[57] CLAIM

The ornamental design for a filter housing, as shown and described.

DESCRIPTION

FIG. 1 is a top view showing my new design for a filter housing;

FIG. 2 is side view thereof;

FIG. 3 is a front view thereof;

FIG. 4 is a side view thereof;

FIG. 5 is a bottom view thereof;

FIG. 6 is a perspective view closed;

FIG. 7 is a perspective view open; and,

FIG. 8 is a rear view thereof.

The cross-hatching represents conventional fabric and is understood to extend throughout the areas represented. The hose is shown broken away in FIGS. 2, 4, and 5 to indicate indeterminate length.
